UNITED STATES PATENT OFFICE.

CLEVELAND C. KING, OF LEWISBURG, ALABAMA.

CHURN ATTACHMENT FOR WASHING MACHINES.

Application filed May 28, 1926. Serial No. 112,399.

My invention relates to a churn attachment for washing machines of the type comprising a vertical standard which drives a dash element for the washer with a partial 5 rotation back and forth in the washing vessel.

The motion obtainable in washing machines of this kind is highly suited to the churning of milk, and I have conceived that 10 washing machines of this type can be readily and easily converted to use as a churn by the removal of the dash from the washing vessel and the substitution of a combination churn vessel and dash, the dash element preferably corresponding to the dash of the washing 15 machine but being integral with the churn vessel so that the churn attachment can be readily substituted for the dash element of the washing machine and operated within the washing vessel.

20 More particularly, my invention contemplates the provision of a churn vessel having its bottom, carrying the dasher elements, surrounding a tubular standard by means of which it is adapted to be mounted on the dash 25 actuating shaft of the washing machine.

My invention further comprises the novel 30 details of construction and arrangements of parts, which will be more fully understood by reference to the accompanying drawings and 35 to the description thereof in the following specification and claims.

According to the drawings:—

Fig. 1 illustrates conventionally the type 35 of washing machine with which my invention is adapted for use as an attachment, the churn attachment shown in section.

Fig. 2 is an enlarged perspective of the 40 churn attachment partly broken away; and

Fig. 3 is a sectional elevation of the cover for the churn attachment.

Similar reference numerals refer to similar parts throughout the drawings.

In the embodiment of my invention illustrated, I have shown the churn applied as an 45 attachment to a typical washing machine 1, comprising a dasher standard 2 which, by the washing machine mechanism that need not be shown or described in detail as the same forms no part of my present invention, is 50 given a partial rotation back and forth about its long axis. In practice the standard 2 is generally rotated through about 270° , and it is provided with suitable bearings and is adapted to fit snugly within a dash sleeve 3 55 which is closed overhead and caused to interlock with the shaft by means of a square

socket 4 engaging a square end 5 on the shaft, or in any other suitable way. This sleeve at its lower end is provided with a circumferential flaring flange 6 which presents an annular concavo-convex face that is traversed by radial fins or dasher blades 7. All of the parts thus far described are standard for the dash of washer machines of the character in question.

To convert this dasher element into a churn, I mount about the outer periphery of the flange a cylindrical vessel 8 having the depth and capacity designed for the churn, and when the washing machine dasher has thus been converted into a churn it is mounted on the standard 2 and the latter is driven with its partial oscillatory rotation, so that the milk will be caused to surge back and forth about the standard and will be agitated by the vanes so that it will be rapidly churned in an efficient and effective manner. After the churning operation, the churn element can be disengaged from the standard 2, and it is of the type which can be readily cleaned and thereafter the standard washer dash without the vessel attachment 8 can be replaced on the standard, thus restoring the machine for washer service.

It is understood that the churn vessel is 85 of a size which can be readily introduced through the top opening 9 in the washing vessel 1 without disturbing the latter.

I provide a suitable lid 10 for closing the top of the churn vessel and which is disposed 90 to clear the top of the sleeve 3 when mounted.

Though I have described with great particularity the details of the embodiment of the invention herein shown, it is not to be construed that I am limited thereto, as 95 changes in arrangement and substitution of equivalents may be made by those skilled in the art without departing from the invention as defined in the appended claims.

Having thus described my invention, what 100 I claim as new and desire to secure by Letters Patent, is:—

1. A churn attachment for machines having a partially rotatable oscillatory vertically disposed shaft, which comprises a sleeve 105 adapted to be mounted for rotation with said shaft, dasher elements secured to the base of said sleeve, and a churning vessel secured to said dasher elements so as to be rotatable with the sleeve, and adapted to hold the milk to be churned in contact with the dasher.

2. A churn attachment for a washing ma-

- chine having a vertical dasher standard which is partially rotatable back and forth about its vertical axis, comprising a dasher element adapted to be mounted on and driven by said standard and comprising an annular bottom member with dasher blades thereover, and a cylindrical marginal wall rising from the periphery of said bottom and adapted to contain the milk to be churned.
5. A churn according to claim 3, in which the dasher means are rigid upright vanes extending radially from said sleeve over the bottom.
10. 3. As an article of manufacture, a churn comprising a receptacle having a cylindrical marginal wall, a removable cover, and a bottom; dasher means secured to said receptacle, and a central sleeve rising axially through the churn bottom and having means to couple it to an oscillatory churn-operating standard.
15. 4. A churn according to claim 3, in which the dasher means are rigid upright vanes extending radially from said sleeve over the bottom.
20. 5. A churn comprising a dasher element formed by a central sleeve, an annular concave bottom and rigid radial vanes crossing the concave bottom, and a vessel body rising from the outer periphery of the dasher bottom.
25. 6. The combination, with a tub of a washing machine, of a driven shaft projecting upwardly within said tub, and a receptacle positively connected with said shaft so as to be turnable therewith, the weight of said receptacle being borne by said tub at the bottom thereof. 30
7. The combination recited in claim 6, together with a sleeve projecting from the inner surface of the tub and encasing the driven shaft. 35
8. The combination recited in claim 6, together with a sleeve projecting from the inner surface of the tub and encasing the driven shaft, and means connecting said sleeve with the receptacle, whereby displacement of the receptacle is prevented. 40
9. The combination with the tub of a washing machine, of a driven shaft projecting upwardly within said tub, and a receptacle positively connected with said shaft so as to be turnable therewith, the weight of said receptacle being borne by said tub at the bottom thereof, and a dasher element within the receptacle. 45
- 50

In testimony whereof I affix my signature.
CLEVELAND C. KING.
